UNITED STATES PATENT OFFICE.

EDWIN J. ARMSTRONG, OF ERIE, PENNSYLVANIA, ASSIGNOR, BY DIRECT AND MESNE ASSIGNMENTS, TO ERIE STEAM SHOVEL COMPANY, OF ERIE, PENNSYLVANIA, A CORPORATION OF PENNSYLVANIA.

METHOD OF AND MECHANISM FOR CONTROLLING VARIABLE-SPEED ENGINES.

Application filed March 17, 1922. Serial No. 544,570.

This invention is designed to improve the performance and efficiency of fluid-actuated engines, such as steam engines, and particularly high speed engines subjected to great variations of load and speed in their normal use, such for example, as hoisting engines with which the invention is particularly advantageous. In carrying out my invention I provide a speed sensitive mechanism which controls the point of cut-off of the engine valve so that this point of cut-off is automatically so adjusted as to get the greatest efficiency, or approximately so, for the speed at which the engine is running and also to give to the engine the greatest speed for a given throttle opening. The speed of the engine is preferably and ordinarily controlled by a throttle so that all that is required of the operator to vary the speed as desired is to operate the throttle in the ordinary manner. With such operation the automatic control of the cut-off controls the engine valve to give both the maximum speed and the maximum economy. With engines of this type the valve ports are ordinarily so proportioned that with a late cut-off and an open throttle a lower speed is attained than with an early cut-off under such conditions because the loss incident to expelling an over-supply of steam more than off-sets the added power of the power stroke. The invention also results in a great saving of steam and gives to the engine under ordinary conditions of operation higher speeds where desired. The invention also involves an improved speed sensitive mechanism which is of peculiar advantage for this purpose. Other features and details of the invention will appear from the specification and claims.

The invention is illustrated in the accompanying drawings as follows:—

Fig. 1 shows a rear elevation of a hoisting engine.

Fig. 1^a a section through the valve chest showing the valve construction.

Fig. 2 a side elevation of the engine.

Fig. 2^a a section through the throttle valve.

Fig. 3 a side elevation of the speed sensitive mechanism, a part being broken away to better show construction.

Fig. 4 a central vertical section of the speed sensitive mechanism.

Fig. 5 a section on the line 5—5 in Fig. 4.

Fig. 6 is a face view of the reversing slot. 55
Fig. 7 is a diagram showing the valve motion.

1 marks the frame of the engine, 2 the cylinders, 3 the crank shaft which is mounted in bearings 3^a on the frame, 4 cranks 60 mounted on the shaft, 5 connecting rods, 6 a cross head to which the connecting rods extend, 7 guides and 8 the piston rod extending from the cross head to the usual piston 8^a. The engines are provided with the usual 65 steam chests 9 in which are arranged the usual valves 9^a operating on the ports 9^b and the exhaust outlets 9^c. Steam is delivered to the steam chest through a pipe 10 and is controlled by a throttle valve 11 which 70 has the sliding valve head 11^a operating over the port 10^a which in turn leads to the pipe 10. The valve is operated by a rock arm 12^a mounted on a shaft 12. The shaft is journaled in bearings 13. A rock 75 arm 14 is fixed on the shaft 12. A link 15 extends from the rock arm 14 to a lever 16. The lever 16 is mounted on a pin 17 carried by the frame. A rod 18 leads from the lever 16 to a convenient point of control. 80 Through this linkage it will readily be seen that the throttle may be operated as desired. The exhaust is carried from the steam chest by way of the pipes 19 which unite in the exhaust pipe 20. 85

A gear 21 is fixed on the shaft 3 and drives a drum gear 22 of the usual construction which operates a drum 22^a with the usual drum controls (not shown). The valves 9^a are reciprocated by valve rods 23 90 which are secured to valve slides 24, the slides being mounted in guides 25 on the engine bed. A rod 26 extends from one of the slides and an eccentric rod 27 from the other of the slides. The rod 27 has an eccentric strap 28. The rod 26 extends to a rock arm 29 which is fixed on a shaft 30. The shaft 30 is carried in bearings 31 on the frame. A rock arm 32 is also fixed on the shaft 30 and is connected by a link 33 with 100 the eccentric strap 28. The purpose of this rock lever 29 is to operate the valve so as to permit the cranks to be placed at an angle to each other in the ordinary manner.

The speed sensitive mechanism is shown 105 in detail in Figs. 3, 4 and 5. It has a carriage 34 which is fixed on the crank shaft by means of a key 35. The carrier is made

2
up of the two side arms 36 which are connected by yokes 37.

The eccentric 38 on which the strap 28 operates is mounted on a pin 39. The pin 39 extends through bearings 40 in the arms 36. The eccentric has an arm 41 which is secured by a screw 42 with an arm 43, the arm 43 having forks 44 and being secured on the pin 39 so as to be concentric with the mounting of the eccentric. A weight 45 is rotatively mounted on a pin 46. The pin has the shouldered ends 47 which extend into slots 48 arranged in the cylindrically shaped inwardly extending lugs 49 on the forks 44. The weight rolls on the eccentric surfaces 50, these eccentric surfaces being opposed to each other made up of an arc of a circle on the center 50^b and struck with a radius 50^b-50^c, the weight rolling on one of these surfaces with the engine running in one direction and operating on the other surface as indicated in dash lines Fig. 3 when running in the opposite direction. The meeting points of the eccentric surfaces 50 at 50^a, it will be observed, are farther from the axis of the crank shaft than other points of said surfaces so that as the weight is rotated with the shaft it tends to roll by reason of centrifugal force toward the point 50^a. The eccentric surface is carried by a frame 51 which is secured by screws 52 to the yokes 37 of the carrier. Spring yokes 53 are provided with the slots 54 which form a sliding fit with the cylindrically shaped lugs 49 on the arms 44. The yokes 53 are connected at their ends by the spring pins 55. Springs 56 are provided with the eyes 57 which are arranged on the pins 55. The springs are mounted on a spring block 58, this block being provided with arms 59 on which the springs rest and the springs being secured to the block by means of bolts 60.

The spring block is journaled on the crank shaft and is provided with a circumferential slot 61. The outer face of this slot has a cylindrical surface 62 in which is arranged a spiral slot 63. A pin 64 operates in this spiral slot and is carried by a reversing bar 65 which is slidingly mounted so as to move axially in the slot 65^a in the carrier arms 36. The bar 65 is secured to a collar 66 slidingly mounted on the shaft 3. The collar has a groove 67 in which a ring 68 is mounted. Lever arms 69 are pivoted on trunnions 70 which extend from the ring 68. The arms 69 are fixed on a shaft 71. The shaft 71 is journaled in bearings 72. An operating lever 73 is fixed on the shaft 71 and operates over a segment 74 with the catch 74^a by means of which the lever 73 may be locked in opposite positions.

It will readily be seen that if the lever 73 is thrown it, operating through the linkage which has just been described, moves the reversing bar 65 and the pin carried with this

reversing bar operating in the spiral slot 63 throws the spring block 58 so as to carry the roller over one or the other of the surfaces 50 and as the roller is thrown from one of these surfaces to the other the arm 44 and with it the arm 41 is swung swinging the eccentric 38 so as to reverse the engine. Incidental with this reversal of the engine it will be noted that the weight 45 will be operating on a reversed eccentric surface so that not only is the engine reversed but the speed sensitive mechanism is also reversed so as to operate perfectly with the reverse conditions. In Fig. 7 I show the diagram of the eccentric motion. In this A represents the center of the shaft, B the pivot upon which the eccentric swings across the shaft, and C the center of the eccentric when in the position shown in Fig. 3. The crank is in the line A-B. As the engine speeds up the centrifugal force of the weight 46 overcomes the resiliency of the spring 56 and moves the center C of the eccentric toward the line A-B, the arc D-E representing its movement between the lowest and highest speed. The direction of rotation under these conditions is anti-clockwise. The distance F-G represents the lap of the valve so that the valve is open from the time the center of the eccentric at C crosses the line G until it again crosses it near C'-something like three-fourths of the piston stroke. As the center of the eccentric C moves in toward the line A-B by reason of increasing speed, the arc during which it is outside of the line G becomes less and when it reaches the line E which is about its limit the valve barely crosses the line G and immediately recrosses it thus admitting a small quantity of steam and during a small portion of the piston stroke. When the device is reversed, the center of the eccentric goes to C', the direction being clockwise and the same effect by increasing the speed takes place, the maximum movement being indicated between D' and E'.

In the general operation of the engine, either going forward or back, the operator simply operates the throttle, opening it farther for a higher speed or heavier load and closing it for a slower speed or less load. In each instance the speed sensitive mechanism responding to this throttle opening and the load with the speed which follows such condition gives to the engine valve a cut-off for this particular speed and this cut-off will give the maximum economy for the speed and if a greater speed is required will give a cut-off which will accomplish the maximum speed which, as I have before stated, will be attained under ordinary conditions with a comparatively early cut-off. These conditions are ordinarily attained by a skilled locomotive engineer but in this instance these conditions are attained by an

ordinary operator actuating only the throttle and where this is used for an engine in which these variations in load and speed are of great frequency not only is there a greater 5 certainty of the adjustment of the valve cut-off to accomplish the greatest economy, or speed, but the operator is relieved entirely of this added attention.

It will be noted that the springs act as 10 the centripetal element tending to move the weight along that part of the surface nearer the axis and that the weight operates as a centrifugal element tending to move to a position away from the axis. It will also 15 be noted that the springs 56 have such a variation of tension, or force that they do not operate to maintain the engine at a constant speed in the manner of an ordinary speed governor. Instead of giving a port opening 20 to the cut-off valve which will bring the engine to a comparatively constant speed this device adjusts the port opening to the speed, the speed being controlled by the throttle, the spring being so adjusted relatively to 25 the weight that the forces balance or there is an equilibrium at speeds throughout the range of speed to which the engine is designed to run. However, the invention may be measurably achieved if the range of control 30 is through the most important parts of the working range.

What I claim as new is:—

1. In a controlling mechanism for fluid actuated reciprocating engines, the combination 35 of an engine valve; devices actuating the engine valve; a centrifugally actuated speed sensitive mechanism responsive to the speed of the engine actuating said devices to vary the point of cut-off of the valve as the 40 speed varies; manually actuated means independent of said devices for controlling the speed of the engine in the normal working range of the engine; and means reversing the 45 devices while leaving them subject to the influence of the mechanism.

2. In a controlling mechanism for variable speed fluid actuated engines, the combination 50 of a manually actuated controlling throttle valve controlling the admission of fluid to the engine to control the speed of the engine; an engine valve; a valve actuating device comprising a centrifugally actuated speed sensitive mechanism responsive to the 55 speed of the engine actuating the engine valve to vary the cut-off as the speed varies; and means for reversing said device while leaving it subject to the influence of said mechanism.

3. In a controlling mechanism for fluid actuated engines, the combination of a manually actuated throttle controlling the speed of the engine; an engine valve; a valve actuating device; a centrifugally actuated speed sensitive mechanism controlling the action 65 of the device as the speed varies to vary the

point of cut-off of the valve; and means for reversing said device while leaving it subject to the influence of the mechanism.

4. In a controlling mechanism for fluid actuated engines, the combination of a manually actuated throttle controlling the speed of the engine; an engine valve; a valve actuating device; a centrifugally actuated speed sensitive mechanism controlling the action of the device as the speed varies to 70 vary the point of cut-off of the valve throughout a major portion of the major part of the range of speed of the engine; and means for reversing said device while leaving it subject to the influence of the mechanism. 75

5. In a speed sensitive controlling mechanism, the combination of a carrier having an eccentric weight carrying surface; a valve actuating device mounted on the carrier; a weight rolling on the carrier surface; a 80 spring resisting the movement of the weight; means conveying the movement of the weight to the device comprising a swinging arm mounted on the carrier; and a trunnion on the weight engaging the arm. 85

6. In a speed sensitive controlling mechanism, the combination of a carrier having an eccentric weight carrying surface; a valve actuating device mounted on the carrier; a weight rolling on the carrier surface; a 90 spring resisting the movement of the weight; means conveying the movement of the weight to the device comprising a swinging forked arm mounted on the carrier; a pin engaging the arm and concentric with the weight; and a connection between the arm and the weight. 95

7. In a speed sensitive controlling mechanism, the combination of a carrier having an eccentric weight carrying surface; a valve actuating device mounted on the carrier; a weight rolling on the carrier surface; a 100 spring resisting the movement of the weight; means conveying the movement of the weight to the device comprising a forked arm swingingly mounted on the carrier; inwardly extending slotted lugs on the forks; a pin in the weight operating in the slots; and a connection between the arm and said device. 105

8. In a speed sensitive controlling mechanism, the combination of a carrier having an eccentric weight carrying surface; a valve actuating device mounted on the carrier; a weight rolling on the carrier surface; springs resisting the movement of the weight; means conveying the movement of the weight to the 115 device comprising a forked arm swingingly mounted on the carrier; inwardly extending slotted lugs on the forks; a pin in the weight operating in the slots; a connection between the arm and said device; and spring yokes 120 engaging the lugs to which said springs are connected.

9. In a speed sensitive controlling mechanism, the combination of a carrier having an eccentric weight carrying surface; a valve 130

43
 actuating device mounted on the carrier; a weight rolling on the carrier surface; springs resisting the movement of the weight; means conveying the movement of the weight to the device comprising a forked arm swingingly mounted on the carrier; inwardly extending slotted lugs on the forks; a pin in the weight operating in the slots; a connection between the arm and said device; and spring 10 yokes engaging the lugs, said yokes being connected by spring pins to which the springs are connected.

10. In a speed sensitive controlling mechanism, the combination of a carrier having 15 an eccentric weight carrying surface; a valve actuating device mounted on the carrier; a roller weight rolling on the carrying surface; means for conveying the movement of the weight to the device comprising a forked 20 arm having inwardly extending slotted lugs; a pin in the roller extending into the lugs; spring yokes engaging said lugs, said yokes having spring pins at each end; and springs resisting the movement of the weight secured 25 to said pins.

11. In a speed sensitive controlling mechanism, the combination of a carrier having an eccentric weight carrying surface; a valve actuating device pivotally mounted on the 30 carrier; a forked arm mounted concentric with the valve actuating device and connected therewith, said forked arm having inwardly extending slotted lugs; a weight between the forked arms rolling on said 35 eccentric surface; a pin on the weight extending into said slots; spring yokes engaging the lugs; and springs connected with the yokes and resisting the movement of the weight.

40 12. In a speed sensitive controlling mechanism, the combination of a carrier having opposed eccentric weight carrying surfaces thereon; a weight engaging said surfaces; a spring resisting the movement of the 45 weight; a valve actuating device controlled by the weight; and means for moving the weight on the surfaces to reverse the action of the weight on the device.

13. In a speed sensitive controlling mechanism, the combination of a carrier having 50 opposed eccentric weight carrying surfaces thereon; a weight engaging said surfaces; a spring resisting the movement of the weight; a valve actuating device controlled by the weight; and means for moving the weight on the surfaces to reverse the action of the weight on the device and for reversing the action of the spring on the weight.

55 14. In a speed sensitive controlling mech-

anism, the combination of a carrier having 60 opposed eccentric weight carrying surfaces thereon; a weight engaging said surfaces; a spring resisting the movement of the weight; a valve actuating device controlled by the weight; and means acting through 65 the spring for moving the weight on the surfaces to reverse the action of the weight and the spring to reverse the speed sensitive controlling mechanism.

15. In a speed sensitive controlling mechanism, the combination of a carrier having opposed eccentric weight carrying surfaces thereon; a weight engaging said surfaces; a spring arm secured to the weight; a movable mounting for the spring arm; and 75 means for shifting the mounting to reverse the spring and the weight on the surface to reverse the speed sensitive controlling mechanism.

16. In a speed sensitive controlling mechanism, the combination of a carrier having opposed eccentric weight carrying surfaces thereon; a weight engaging said surfaces; a spring arm secured to the weight; a movable mounting for the spring arm; means 85 for shifting the mounting to reverse the spring and the weight on the surface to reverse the speed sensitive controlling mechanism comprising an axially moving reversing device; and a spiral connection between 90 the spring mounting and said reversing device.

17. In a speed sensitive controlling mechanism, the combination of a carrier formed 95 with two sides and a frame carrying an eccentric weight engaging surface; a weight arrangement on said surface; a forked arm journaled between the sides of the carrier in which the weight is mounted; a valve actuating device connected with the forked 100 arm; a spring block concentric with the carrier; springs mounted on the block and resisting the movement of the weight; an axially moving reversing device mounted in the carrier; and a spiral connection between 105 said device and spring block for reversing the same.

18. In a speed sensitive controlling mechanism, the combination of a centrifugal weight; a spring opposing said weight; a 110 valve actuating device controlled by the weight; and means for reversing the spring and action of the weight on the valve actuating device.

In testimony whereof I have hereunto set 115 my hand.

EDWIN J. ARMSTRONG.
